[57] CLAIM

The ornamental design for a set of holders for water tank storage units for an emergency vehicle, as shown and described.

DESCRIPTION

FIG. 1 is a front perspective view embodying our new design;

FIG. 2 is a side elevation view as shown from the left of FIG. 1;

FIG. 3 is a front elevation view;

FIG. 4 is a side elevation view as shown from the right of FIG. 1;

FIG. 5 is a top plan view;

FIG. 6 is a bottom plan view; and,

FIG. 7 is a rear elevation view.

The broken lines shown in FIGS. 1, 3, 5, 6 and 7 are for illustrative purposes only and form no part of the claimed design.
